UNITED STATES PATENT OFFICE.

JAMES E. HENRY, OF SHEBOYGAN, WISCONSIN, ASSIGNEE OF ONE-HALF TO
THE C. REISS COAL COMPANY, OF SAME PLACE.

HOISTING-BUCKET.

SPECIFICATION forming part of Letters Patent No. 650,642, dated May 29, 1900.

Application filed March 12, 1900. Serial No. 8,272. (No model.)

To all whom it may concern:

Be it known that I, JAMES E. HENRY, a citizen of the United States, and a resident of Sheboygan, in the county of Sheboygan and State 5 of Wisconsin, have invented certain new and useful Improvements in Hoisting-Buckets; and I do hereby declare that the following is a full, clear, and exact description thereof.

My invention has for one object to provide 10 for closing separable hoisting-buckets by means of compressed air or other fluid under pressure; and a further object of the invention is to provide for automatic opening of said buckets, said invention consisting in certain 15 peculiarities of construction and combination of parts hereinafter particularly set forth with reference to the accompanying drawings and subsequently claimed.

Figure 1 of the drawings represents a sectional view of a separable hoisting-bucket provided with closing and opening mechanism in accordance with my invention; Fig. 2, an elevation of what is shown in the first figure, the sections of the closed bucket being broken; 25 and Fig. 3, a partly-sectional view indicated by lines 3 3 in the second figure.

Referring by letter to the drawings, A indicates each of a pair of sections constituting a separable hoisting-bucket. Each bucket-section is provided with inner upper corner side ears b, and the ears of one section are in pivotal connection with the ears of the other section. Shouldered studs c, extending inward from the ear corners of the bucket-sections, have their reduced ends engaged with slots d in arms e of a cross-head B on the outer end of a rod C, rigid with a piston D in a vertical cylinder E, connected by links F to the upper outer corners of said bucket-sections. 30 As a matter of detail the upper cylinder-head is shown provided with hollow central cross-lugs f, and a pivot-pin g, extending through the lugs, engages eyes in the upper ends of the links F, the lower ends of these links being 35 also in pivotal connection with the bucket-sections.

Engaging the pivot-pin g, between the cylinder-head lugs, I show a hanger G for connection with a hoisting-cable; but the details 40 of construction latterly specified are suscep-

tible of variation in practice without change of result—as, for instance, it would be practical to provide the upper cylinder-head with lateral pivot-studs for the aforesaid links and a central ring-bolt for the hoisting-cable.

55

Pivots secured in apertures h of the cross-head B are latches H, and leaf-springs I, made fast on said cross-head, oppose the latches. When the piston D is run up in cylinder E to bring the bucket-sections together, the spring- 60 opposed latches snap on the lower cylinder-head, and thus the bucket is held closed, as best shown in Fig. 3. When the latches are caught on the lower cylinder-head, their beveled heads are in the way of a spanner J, having an upwardly-extending lever-shank J' in pivotal connection with ears i, extending laterally from the aforesaid cylinder, the construction and arrangement of the spanner being such that its downward tilt will operate 65 to displace said latches and permit automatic opening of the bucket. In practice it is designed that a striker K (indicated in Fig. 1) shall be arranged in the path of the spanner-shank and that contact of these parts will result in automatic release of said latches.

70

75

In connection with the lower cylinder-head I show a tubular elbow-fitting L, having a centrally-apertured packing-disk j held in its upper free end, and designed for insertion in 80 the packing-disk is the tapered nozzle k of a conveyer M for compressed air or other fluid under pressure. By admission of fluid under pressure in cylinder E under piston D the latter is elevated to effect a closing of the bucket, 85 as will be readily apparent by especial reference to Fig. 1.

In practice the open bucket is lowered into a mass of material to be elevated and an attendant positions the nozzle of conveyer M in 90 the packing-disk of fitting L to inject fluid under pressure into cylinder E for the purpose of closing said bucket and causing engagement of its spring-latches with the lower cylinder-head, after which said nozzle is withdrawn and the hoisting operation takes place, the opening of the aforesaid bucket being subsequently effected by release of said latches incidental to tilt of spanner J in the proper direction automatically or otherwise.

95

100

Having thus described my invention, what I claim as new, and desire to secure by Letters Patent, is—

1. A separable hoisting-bucket having its sections in pivotal union, a cross-head with which the bucket-sections have slide connection, a cylinder in link connection with said bucket-sections and provided with an inlet designed to have tight temporary connection with a nozzle of a conveyer for fluid under pressure, a piston in the cylinder opposed to inflow of said fluid, a rod connecting the cross-head and piston, latches in connection with the cross-head automatically engageable with said cylinder, and a latch-retracting spanner in pivotal connection with the aforesaid cylinder.
2. A separable hoisting-bucket having its sections in pivotal union, a cross-head with which the bucket-sections have slide connection, a cylinder in link connection with said bucket-sections and provided with a tubular fitting containing an apertured packing-disk for the temporary engagement of the nozzle of a conveyer for fluid under pressure, a piston in the cylinder opposed to inflow of said fluid, a rod connecting the cross-head and piston, latches in connection with said cross-head automatically engageable with said cylinder, and means for retracting the latches.
3. A separable hoisting-bucket having its sections in pivotal union, a cross-head with which the bucket-sections have slide connection, a cylinder in link connection with said bucket-sections and provided with an inlet designed to have tight temporary connection

with a nozzle of a conveyer for fluid under pressure, a piston in the cylinder opposed to inflow of said fluid, a rod connecting the cross-head and piston, latches in connection with the cross-head automatically engageable with said cylinder, and a latch-retracting spanner in pivotal connection with the aforesaid cylinder.

4. A separable hoisting-bucket having its sections in pivotal union, a cross-head having slotted arms engaged by studs on the bucket-sections, a cylinder in link connection with said bucket-sections and provided with an inlet designed to have tight temporary connection with a nozzle of a conveyer for fluid under pressure, a piston in the cylinder opposed to inflow of said fluid, a rod connecting the cross-head and piston, latches in connection with said cross-head automatically engageable with said cylinder, and means for retracting the latches.

5. A separable hoisting-bucket, and means in conjunction therewith for the utilization of fluid under pressure as a closing medium, latch mechanism for holding the bucket closed, and latch-retractive mechanism.

In testimony that I claim the foregoing I have hereunto set my hand, at Sheboygan, in the county of Sheboygan and State of Wisconsin, in the presence of two witnesses.

JAMES E. HENRY.
